Primary Examiner — Jennifer L Watkins*Assistant Examiner* — Samantha Lynne Brodowski*(74) Attorney, Agent, or Firm* — Suzanne Kikel, Patent Agent(57) **CLAIM**

The ornamental design for a purse with flap in shape of Oklahoma, as shown and described.

DESCRIPTION

FIG. 1 is a front perspective view of a purse with flap in shape of Oklahoma with the flap in a close position, showing my new design;

FIG. 2 is a front elevation view thereof;

FIG. 3 is a rear elevation view thereof;

FIG. 4 is a left side view thereof;

FIG. 5 right side view thereof;

FIG. 6 is a top plan view thereof;

FIG. 7 is a bottom plan view thereof; and,

FIG. 8 is a front perspective view thereof with the flap in an open position.

The evenly dashed broken line showing of a handle depicts environment and forms no part of the claimed design. The dash-dot-dash broken line showing of the inside of the purse depicts a portion of the article and forms no part of the claimed design.
